Application July 29, 1932, Serial No. 625,610

8 Claims. (Cl. 179—170)

The present invention relates to power supply for space discharge repeaters or other apparatus in a telephone system or similar system.

The invention relates specifically to provisions for energizing repeaters in unattended repeater stations and will be described in connection with such a system, although it is capable, in certain respects at least, of other uses as will appear from the scope of the claims.

10 Repeater stations on voice frequency cables are spaced about fifty miles apart. When high frequency carrier channels are superposed on the cable conductors, it is necessary or desirable to use a closer repeater spacing, for example, half 15 of the fifty-mile span, or one third, or even less, depending upon conditions. With these closer repeater spacings, it is uneconomical to duplicate at each repeater point the equipment that is provided at the fifty-mile repeater stations. Such 20 equipment includes a permanent building with normal and stand-by sources of power, testing equipment, etc., and requires one or more attendants continuously.

25 The invention contemplates an intermediate repeater station comprising a minimum of apparatus, requiring no continuous attendance at the station, and capable of functioning under both the conditions of normal and emergency power supply.

30 An object of the invention is an economical and thoroughly reliable power supply for line repeaters or the like located at a distance from a terminal or main repeater station.

35 Aside from apparatus failure (such as failure of tubes, etc.) with which the present invention is not specifically concerned, the principal emergency condition to provide against in an unattended repeater station is failure of the power supply, either the plate supply or the cathode heating supply. An interruption of the plate voltage supply, for example, practically immediately 40 interrupts the service. The plate voltage could be maintained by a floating storage battery, but such a storage battery located at an unattended repeater station would be both bulky and unreliable if unattended for long periods of time. The present invention uses a voltage source 45 at the main repeater station as the plate supply for the tubes at an unattended repeater station and supplies this current over the telephone lines. This source includes a floating battery which insures against interruption of plate voltage at the unattended repeater station.

50 The cathode heating power requirements are rather heavy especially where heater type tubes

are used. It would be expensive to supply this current continuously from the main station over the telephone circuits. The invention provides for a local supply of the relatively large heating current power required, and as an emergency 5 supply to bridge over power failures in such local supply, provides for sending an increased amount of current over the telephone lines themselves from the main station. The thermal capacity of the cathodes permits the switch-over 10 from regular to emergency power supply to be made without any interruption in service, even though the power failure should occur in the midst of a conversation. Since the time that the local power is off probably aggregates only one or 15 a very few hours a year, the expense item in sending the cathode heating power over the telephone line is practically confined to the cost of the emergency apparatus involved, which is small because it can be made common to a large number 20 of lines.

A typical system to which the invention might be applied is a telephone toll cable providing twenty-four carrier speech channels per pair in the frequency range 8 to 100 kc. The connections for superposing direct current on the pairs in multiple might appear, at first sight, to produce a prohibitive amount of cross-talk. The use of small and inexpensive choke coils in the direct current connections to the individual lines, however, aids in keeping the cross-talk due to this cause down to practical limits.

30 A better understanding of the invention will be had from the following detailed description of a typical embodiment as represented in the accompanying drawings in which:

35 Figs. 1 and 2 are simplified diagrams showing two types of connections that may be employed with the invention, between terminal or main repeater stations and an unattended repeater station, while

40 Figs. 3, 4 and 5, when placed together with Fig. 3 at the top, and Figs. 4 and 5 underneath in the order named, show in greater detail the power supply circuit for an eastward repeater and 45 a westward repeater on an east line and west line, respectively, these being representative of a group of repeaters and lines, the circuits of which are arranged similarly to those shown.

45 Referring to Fig. 1, west, intermediate and east stations are shown operating on a four-wire basis with all of the west-to-east lines grouped in one cable C_E and with all of the east-to-west lines grouped in a separate cable C_w. It is assumed that each of these cables contains one hundred 50

pairs, although the invention is not dependent upon the use of any particular number. It is also assumed that each pair of lines may be multiplexed to transmit a number of voice modulated carrier waves, for example, twenty-four carrier waves extending from about 8 kilocycles to 100 kilocycles.

The west and east stations may be terminal stations but it will be assumed in the present description that they are repeater stations of the attended type and that the intermediate station is unattended. At each of these repeater stations there will be one repeater per line, designated for convenience A_1 to A_{100} , of which only two, A_1 and A_{100} , are illustrated at each of the repeater stations for each direction of transmission.

As will be described more fully later on, these repeaters are of the type employing space discharge tubes having cathodes which require to be heated and anodes which require the supply of steady plate voltage thereto. The cathode heating current is supplied in accordance with the present disclosure from alternating current mains local to each of the repeater stations. This local filament supply is not indicated at the west and east stations but is shown at 10 for the intermediate station.

The plate supply for the intermediate repeater is derived from rectifier units 11 and 12 located respectively at the west and east stations. These rectifier units supply rectified and filtered current over the line wires from the attended repeater station to the unattended station. In the case of rectifier unit 11, this current, for example, extends from the positive terminal of the rectifier, lead 14, choke coils 15, 15 in parallel, one for each line, the 100 pairs of line wires in the cable C_E in multiple to the intermediate station; retard coils 16, 16, one for each line in multiple, bus-bar 17, the plate circuit of each of the amplifiers A_1 to A_{100} , inclusive, in the west-to-east cable at the intermediate station over supply leads 18, 18, etc., and 19, 19, etc., bus-bar 20, retards 21, 21 in parallel, the 100 pairs of lines in the cable C_w , retards 22, 22 in parallel and back through lead 45 14' to the minus pole of the rectifier unit 11. Thus it is seen that the anode voltage for all of the repeaters at the intermediate station in the west-to-east cable is supplied from the rectifier unit 11 of the west station.

In a similar manner, the plate voltage for all of the repeaters at the intermediate station in the east-to-west cable C_w is supplied from the rectifier unit 12 at the east station. The circuit for supplying the latter is entirely analogous to that previously traced and comprises the positive pole of rectifier unit 12, retard coils 23, 23 in multiple, the 100 pairs in the cable C_w to the intermediate station, retard coils 24, 24 in multiple, to the plate circuits of all of the 100 repeaters A_1 to A_{100} , all of the retards 25, 25 in multiple, the 100 pairs in the cable C_E in multiple, retard coils 26, 26 in multiple and so back to the minus pole of rectifier unit 12.

As already stated, the cathode heating current for all of the repeaters at the intermediate station, is supplied locally from the supply mains 10. In case of failure of this local supply the two inverters 27, 28 at the intermediate station are brought into play to supply the cathode heating current from the east and west repeater stations, respectively, as will be more fully described hereinafter.

In the alternative arrangement in Fig. 2, the west-to-east group of lines and the east-to-west 75 group of lines are all included within the same

cable sheath, and suitably shielded from each other. The lines within the cable are operated on a four-wire basis the same as in the case of Fig. 1, but the oppositely directed lines are now included in the same cable instead of in two separate cables as in Fig. 1. Assuming a 100 pair cable there will be 50 lines transmitting west to east and 50 lines transmitting east to west with 50 east repeaters and 50 west repeaters at each station. Except for this, the circuits are identical with those described in Fig. 1. In the circuit of Fig. 1 all of the lines within one cable will be of the same direct current potential, whereas in the circuit of Fig. 2 a difference of potential equal to the rectifier voltage will exist between the east 15 lines and the west lines as groups.

Referring to Figs. 3, 4 and 5 together, the identity of several of the elements with those shown on Figs 1 and 2 will be recognized from the use of similar reference characters. With Fig. 4 placed above Fig. 5 and Fig. 3 placed above Fig. 4, it will be noted that the apparatus is aligned in vertical columns, the elements at the left of each of these figures being located at the west station (as in Fig. 1), while the remainder of the apparatus is located at the intermediate station, the separation being indicated by the use of dotted lines in the circuits interconnecting these two groups of apparatus. For simplicity in Figs. 3, 4 and 5 the apparatus at the east station has been omitted.

In Fig. 3 two of the amplifiers A_1 and A_{100} for the west station are shown connected by the two corresponding west-to-east lines with repeaters A_1 and A_{100} of the intermediate station, A_1 at this station being shown in detail (at 300) as will be explained later.

The positive lead 14 connected to the retard coil 15 of Fig. 3 extends in Fig. 4 to the positive terminal of the rectifier 11. There is also indicated on Fig. 4 the inverter 27 of the intermediate station.

In Fig. 5 a diagrammatic showing is given of inverter 28 of the intermediate station together with two of the amplifiers at that station A_1 and A_{100} , connected by a corresponding east-to-west line with the repeaters A_1 and A_{100} of the west station. Retard coils 22, 22 are shown connected to the west terminals of these lines and to lead 14' extending to the negative pole of the rectifier 11 of Fig. 4.

All of the repeaters A_1 to A_{100} of the intermediate station may be alike so that only one amplifier 300 of Fig. 3 has been illustrated in detail. Each of these repeaters or amplifiers is assumed to be designed to transmit the frequency range 8 to 100 k. c. comprising, for example, 24 speech channels each of about 3000-cycle width with a spacing of about one kilocycle between channels. While any suitable type of amplifying repeater might be used in this system, it is preferred to use a type of amplifier disclosed and claimed in U. S. application for Letters Patent of H. S. Black, Serial No. 606,871 filed April 22, 1932, that illustrated being similar to the circuit of Fig. 65—A 65 of the Black application. For ease in comparison similar reference characters will be used in describing this amplifier to those used in the Black application referred to.

This amplifier is shown as comprising two pentode tubes 301' and 302' in cascade leading into a third tube 303 of the coplanar grid type. This amplifier is provided with a negative feed-back generally indicated at 29, between its final output and its initial input. The feed-back includes an 75

equalizer 30 for giving the amplifier circuit as a whole a characteristic such as to compensate for the unequal attenuation of the line over the frequency range transmitted. The amplifier may, for example, have a gain throughout the frequency range from 8 kilocycles to 100 kilocycles of the order of 100 db. without any feed-back, while with the negative feed-back employed the gain may be reduced at 8 kilocycles to the order of 20 db. or less and at 100 kilocycles to the order of 60 db. As pointed out more fully in the Black application, this reduction in the gain greatly increases the stability of the amplifier and also greatly reduces modulation or, in other words, improves the quality. The 40 db. difference between the 8 kilocycle and 100 kilocycle gains with the feed-back is obtained by means of the equalizer 30.

The tubes 301' and 302' are preferably Western Electric Company type 7592-A having an amplification factor of approximately 1000 and a plate impedance of approximately 700,000 ohms. The tube 303 is preferably of the general type disclosed by H. A. Pidgeon and J. O. McNally in their copending application, Serial No. 368,647 filed June 5, 1929, which has become Patent No. 1,923,636 or in their copending application, Serial No. 542,252 filed June 5, 1931, which has become Patent No. 1,920,274 or in a paper by Pidgeon and McNally in the Proceedings of the Institute of Radio Engineers, volume 18, pages 226 to 293, February 1930.

It will be noted that the various points of the circuit of the amplifier 300 that would ordinarily be grounded are in this instance connected to the lead 19 which is in turn connected to bus-bar 20 leading to the return path through the east-to-west line and eventually to the west station rectifier 11, negative pole. A direct circuit to ground at the intermediate repeater point for any of the leads of the amplifier 300 is avoided since the anode voltage supply circuit is a full metallic circuit over the transmission lines of the west and east cables, respectively. Conductor 19 may, however, be taken as a point of reference for the various voltages existing in the amplifier 300 at the intermediate repeater station.

One reason for omitting ground connections at the repeater points is to prevent trouble caused by electrolysis currents flowing back over the cable pairs. These currents might be quite large and, in some cases, might become so high as to blow the amplifier fuses. Another reason for omitting these grounds is to prevent danger to workers on the line, since without the ground connections there is no possibility of a shock between ground and a cable pair.

Various condenser-resistance combinations CR, CR, etc. are shown connected between the direct current supply leads and ground, to cooperate with the retards 15, 16, 21, 22, etc., in reducing cross-talk. These resistances are so high as to amount merely to direct current leak paths and are not grounds in the sense discussed in the next preceding paragraph.

The cathodes of tubes 301' and 302' are connected to conductor 19 through resistors 343 and 353, respectively, each of which is bridged by a condenser 366 or 369 which serves as a by-pass for alternating current. The series resistances mentioned serve to provide bias for the operating grids. Similarly, the filament of tube 303 is connected to conductor 19. Plate potential is supplied from conductor 18 to the anodes of the three repeater tubes through resistors 368, 371 and the primary of output transformer 318. The con-

densers 340 and 350 afford an alternating current by-pass to the common conductor 19. The screen grid of each pentode is connected through a corresponding resistance 360 or 361 to the anode supply lead 18 and shunting condensers 367, 370, respectively are used to by-pass alternating current around these resistances.

The three stages are interconnected by means of impedance type of couplings through the series condensers 364 and 365, respectively. The plate supply for pentode 301' from resistance 368 as described continues through a network 31 which together with the other elements of the circuit including a similar network 32 for pentode 302' is designed to give the amplifier circuit as a whole the proper gain and phase shift characteristic. One of the two grids of tube 303 is biased negatively from battery 332 connected through resistances 333, 334, the former of which is shunted by condenser 372 so that it does not form a part of the coupling impedance between the last two stages. The other grid of the coplanar tube 303 is biased positively by battery 335 connected through series resistance 336 and shunted by capacity 313 for by-passing alternating current. With the high amplification and large values of feed-back employed in this amplifier, the absolute value of the gain and the phase shift should be carefully controlled to avoid danger of singing. The various circuit elements shown in the amplifier are sufficient and capable with proper choice of constants to give satisfactory results. For a more detailed description of the theory of operation and design reference should be had to the Black application above referred to.

As is explained more fully in the Black application, supra, the equalizer 30, being in the feed-back circuit rather than in the direct transmission path, has a characteristic similar to that of the line which is to be equalized rather than the inverse of the line characteristic as would be the case if the equalizer were located in the direct transmission path.

Cathode heating current for all of the cathodes of this amplifier is supplied from the transformer 33 connected to leads 34.

In Fig. 4 the rectifier 11 may be any suitable type of rectifier circuit such as a full wave rectifier for supplying the proper direct-current voltage from its output. The rectifier illustrated comprises tubes 35 and 36 of space discharge type connected by transformer 37 with the alternating current main 38. It will be assumed that this rectifier as a whole develops a terminal direct-current voltage of the order of 200 volts. A battery 39 is floated across the output of the rectifier. This rectifier circuit may also be equipped with any desired amount of filtering comprising series impedance and shunt impedance for delivering a smooth direct current. A unidirectional device such as a copper oxide rectifier is shown at 40 for enabling battery 39 to discharge into the load circuit but for limiting the current through the battery when the rectifier voltage is increased in a manner to be described.

The inverter 27 shown on Fig. 4 is an adaptation to the purposes of the present invention of the Thyratron inverter known in the prior art and described, for example, in "Electronics" for April 1931, pages 581 and 582, in an article by Baker, Fitzgerald and Whitney entitled "Electron tubes in industrial service" (McGraw-Hill Publishing Company, New York, N. Y.). When direct current voltage is applied to the terminals of this inverter, the circuit is set into oscillation

and is caused to produce alternating current in its output circuit, the frequency of which is determined by the constants of the circuit. In the present case, when the alternating current supply 10 at the intermediate station fails, some of the direct current energy sent over the line is applied to the inverter 27 in a manner that will be described more fully hereinafter and is converted by the inverter into alternating current which is applied to the cathode heating circuit of the amplifier at the intermediate station. The number of amplifiers which one inverter 27 is capable of supplying will depend, of course, upon the power required for the amplifiers and the rating of the inverter tubes, but it will be assumed for present purposes that inverter 27 supplies cathode heating current to sixteen amplifiers. A bank of six inverters like 27 will, therefore, be required for each one hundred amplifiers and a small inverter unit may be provided to take care of the additional four amplifiers. To guard against possible power failure of an inverter, each bank of inverters is provided with a spare inverter, one of which is shown at 41. The equipment shown diagrammatically on Fig. 5 may be a duplicate of corresponding apparatus described in connection with Figs. 3 and 4 and hence has not been illustrated in detail. The nature and purpose of this apparatus will be made clear from the description of the operation to follow.

Operation

Each of the west-to-east signaling lines of which two are shown in Fig. 3 may be assumed, as already stated, to be transmitting normally message waves of the frequency range 8 to 100 kilocycles. This band of waves in the case of each line is repeated at each of the repeater stations, two of which are shown in Fig. 3. All the repeaters or amplifiers at the various repeating stations may be identical with that shown in detail at 300 in Fig. 3 or they may be of any other suitable type. At the same time the east-to-west lines, two of which are shown in Fig. 5, transmit a similar range of frequencies in the westward direction which are similarly amplified at the various repeater stations.

Cathode heating current for the tubes of amplifier 300 as well as for each of the other amplifiers at the intermediate repeater station is supplied from mains 10. In the case of the amplifiers of Fig. 3 the circuit is from source 10, leads 42, normally closed back contacts of relay 43, leads 34, transformer 33 to the cathode heating circuit of amplifier 300 and through a transformer similar to 33 for each of the other amplifiers of the west-to-east group. Circuit 44 similarly supplies filament heating current to the amplifiers of Fig. 5.

Rectifier 11 at the west station, Fig. 4, normally supplies a direct current voltage of about 200 volts to the leads 14, 14'. The circuit by which this voltage is applied to the anodes of the tubes of the west-to-east group of repeaters at the intermediate station, Fig. 3, has already been traced and extends through the retard coils 15 in parallel, all of the 100 (or 50 in the case of a circuit layout of Fig. 2) lines transmitting west to east, retard 16 in parallel, conductor 17, conductors 18 in multiple, one for each repeater, the space paths of all of the repeater tubes in parallel, conductors 19 in parallel, one for each repeater, conductor 20, retard coils 21 in parallel, the group of east-to-west lines (Fig. 5), the group

of retard 22 in parallel back to conductor 14' and rectifier 11. It will be assumed that with 200 volts developed by the rectifier the voltage actually available at the intermediate repeater point is 172 volts.

By an entirely analogous circuit as was explained in connection with Fig. 1, the east-to-west group of repeaters in Fig. 5 are similarly supplied with plate voltage from the east station, one side of the circuit comprising the east-to-west lines in parallel and the other side comprising the west-to-east lines in parallel between the intermediate station and the east station.

Bridged across conductors 42 of Fig. 4 are two relays 45 and 46 operating on alternating current and having marginal characteristics such that under normal voltage supply conditions, the armatures of both relays maintain their contacts open. In case of an abnormal condition in the alternating current supply circuit 10 such as an interruption of service, an over-voltage or an under-voltage condition, one or other of relays 45, 46, causes its armature to close its contacts. For example, relay 45 releases when the supply is interrupted or falls below a predetermined value, closing its back contacts. Relay 46 energizes if the voltage increases beyond a predetermined limit and closes its contacts. In either event a circuit is closed for relay 47 extending from conductor 17, winding of relay 47, one or the other of the contacts of relays 45, 46, to conductor 20 so that some of the direct current voltage projected over the lines from the west repeater station is applied to relay 47 causing it to operate. In operating, relay 47 connects the direct current supply conductors 17 and 20 directly to the direct current input leads 48 of the inverter 27. The Thyratron tubes of this inverter have heater type cathodes which, up to the moment under discussion, have been supplied with cathode heating current from leads 34 through branch circuit 49, thus holding the inverter tubes in readiness for immediate operation. At the moment when the direct current voltage is applied to terminals 48, therefore, the inverter 27 becomes operative to produce at its output terminals 50 alternating current of the same voltage and frequency as is normally supplied from circuit 10, for example, 55 volts, 60 cycles. The presence of this alternating current in leads 50 causes operation of relay 51. Relay 43 is at this time operated, it having been energized at the same time that relay 47 was energized, the circuit extending from conductor 17 through lower contacts of relay 47, winding of relay 43 and upper contacts of relay 47 to conductor 20. With relays 43 and 51 both energized the alternating current produced across the output 50 of inverter 27 is applied directly to conductors 34 leading to the cathode heating circuit of the tubes of repeater 300 and the other west-to-east repeaters grouped with it, assumed in the present case to comprise sixteen repeaters supplied from inverter 27. The remaining ones of the eastward repeaters are similarly supplied from other inverters which may also be connected to leads 42, these leads being shown as extending above inverter 27 in Fig. 4. It will be understood that the direct current supply leads 17 and 20 are also multiplied to these other inverters by leads not shown in the drawings.

The foregoing operation takes place as stated for either interruption of supply in circuit 10 or for abnormal over-voltage or abnormal under-voltage and by an entirely analogous procedure

inverter 28 and the other inverters associated with it continue the supply of cathode heating current to each of the east-to-west repeaters A1 to A₁₀₀ of the intermediate station, Fig. 5. The 5 cathodes of the tubes in all of these repeaters have sufficient heat capacity to bridge over momentary interruption of cathode heating supply current without interrupting service.

When the inverters 27 were brought into operation by relay 47 as described, a considerable load was added to the normal load across conductors 17 and 20 and therefore was put on the rectifier 11 at the west station. If no increase were made in the voltage supplied by rectifier 11 the plate voltage 10 of the repeaters at the intermediate station may be assumed to have fallen from its normal value of 172 volts to much below 150 volts. As has been described, the repeaters, such as repeater 300, are designed to have a high degree of stability so that a decrease of plate voltage to the order of 150 volts has but little, if any, effect on the operation of the repeaters and no interruption of service results. Rectifier circuit 11, therefore, is designed to supply an increased output 15 voltage under the abnormal conditions of operation that have been described, sufficient to provide a plate voltage of 150 volts. The rectifier includes marginal relay 53 and relay 54 which are normally unoperated but are caused to operate 20 when the inverters at the intermediate station are brought into operation with consequent increase in drain on the rectifier circuit. When relay 53 operates it closes the circuit for relay 54 causing the latter to shift its armature from its 25 upper to its lower contact and thus to increase the step-up-voltage ratio of transformer 37 by including a smaller number of turns in the primary. For example, the rectifier output voltage may be increased from the normal value 200 to the order 30 of 285 volts, thus maintaining the repeater anode voltage at 150 volts at the intermediate station.

When the power supply conditions at the intermediate repeater return to normal, the circuits are restored to their normal condition by restoration of relays 45 and 46 which control the connection of inverter 27 through the agency of relays 47 and 43; the restoration of the inverters in turn causing release of relays 53 and 54 in rectifier circuit 11 at the west station. Relay 54 in releasing restores the rectifier voltage to its 35 normal value.

The group of inverters 27 comprising the order of six or seven inverters for supplying emergency cathode heating current to the 100 west-to-east repeaters at the intermediate station, as stated, 40 are provided with a spare inverter 41 which is brought into service in case of failure of any one of the inverters 27. For this purpose, the leads 52 and 58 are multiplied to the other inverters of the group. Under abnormal power conditions 45 all of the relays 47 for the group of inverters are operated simultaneously as are also all of the relays 43. Whether or not any one relay 51 operates depends upon whether the corresponding inverter 27 develops alternating current across its 50 output terminal 50 sufficient to operate the relay 51. If relay 51 remains unoperated after corresponding relays 47 and 43 operate, a circuit is closed for relay 55. This circuit is traceable from upper contact of relay 47, winding of relay 55, 55 lower armature and front contact of relay 43, and back contact of the relay 51 in question to the lower contacts of relay 47. The lowermost armatures of all of the relays 43 of the group of inverters 27 are multiplied by means of conductor 56

so that the circuit above traced for relay 55 is closed in case any of the relays 51 remains unoperated in the bank of inverters. Relay 55 in operating applies the direct current voltage from leads 17 and 20 to the direct current terminals 5 of 57 of the spare inverter 41 causing this inverter to develop alternating current of the proper voltage and frequency across its output terminals. Relay 58 is energized when relay 55 attracts its armatures. Relay 58 in its normal unoperated 10 condition maintains the cathodes of the spare inverter 41 hot by supplying current from conductors 34. When energized relay 58 supplies to the cathodes of the inverter 41, the necessary filament heating current developed in this inverter. 15 The alternating current developed by the spare inverter 41 is also applied to conductors 52 which are multiplied to the back contacts of all of the relays 51 in the bank of inverters. The alternating current output for the spare inverter is therefore over conductors 52 and back contacts of relay 51 of the particular inverter which fails to operate and thence over the front contacts of corresponding relay 43 to output circuit 34.

If all of the inverters 27 in a bank are operative when the corresponding relays 47 are energized, relay 55 remains unoperated. If one of the inverters 27 fails to develop enough alternating current power to cause its relay 51 to energize, thus causing relay 55 to attract its armatures, it 25 will be noted that a locking circuit is closed through the extra windings of all of the relays 51 that are operated, this circuit extending through the upper armature and front contact of relay 55, conductor 69, extra windings on operated relays 51 in parallel, upper armatures and front contacts of these relays, and multiple conductor 61 to feed wire 17. This prevents putting excess load on the spare inverter 28 in case of subsequent failure of one of the inverters 27, since the relay 40 51 of the latter is not allowed to release.

It was mentioned above that the condenser-resistance circuits CR are provided to aid in reducing cross-talk. The condensers in conjunction with the retards 15, 16 etc., form filters which 45 allow direct current to pass over the lines but prevent the setting up of high frequency voltages between pairs. The resistances are included as a safety measure. They serve as leaks to prevent the building up of a charge between the lines and ground such as might result in shock to a workman. Also, the resistances equalize the voltage 50 between the cable and ground so that the maximum voltage that can exist between cable and ground is one-half the supply voltage if no direct 55 ground is placed on one side of the direct-current supply.

What is claimed is:

1. In combination, a terminal station, a distant repeater station, a plurality of telephone pairs 60 extending between said stations, an amplifier per pair at said repeater station, each including a space discharge device having anode and cathode, a second plurality of telephone pairs extending between said stations a source of voltage at said terminal station connected to impress a difference of potential between the first plurality of pairs in multiple and the second plurality of pairs in multiple, a circuit at said repeater station connected between said first plurality of pairs in multiple and said second plurality of pairs in multiple, and including the space paths of said amplifiers in multiple, whereby anode potential is supplied to said amplifiers.

2. The combination defined in claim 1 in which 75

- the connections between said source and said lines, and the connections between said lines and said circuit at said repeater station, contain impedance means preventing each line from cross-talking 5 into other of said lines.
3. In a telephone system, an east group of lines and a west group of lines extending between stations, space discharge repeaters at the east station for certain of said lines, each having a 10 cathode adapted to be heated, a source of current at the west station, a circuit supplying current from said source to the space paths of said repeaters comprising said east lines in multiple as one side of the circuit and said west lines in multiple as the opposite side of the circuit and means 15 at said west station controlled over said circuit and actuated in response to a change in load condition at said east station for supplying over said same circuit from said source of current at the 20 west station current for heating the cathodes of said repeaters.
4. In a telephone system, a telephone line, a main station, a repeater station on said line, a space discharge amplifier at said repeater station 25 requiring energizing current, a local supply of said energizing current at said repeater station, and means controlled over said line and automatically operative upon failure of said local supply for transmitting current from the main station 30 over said line to energize said amplifier.
5. In a telephone system, a line, a main station and a repeater station on said line, a source of direct current voltage at the main station, a space discharge amplifier at the repeater station 35 having an anode and a cathode requiring heating, a circuit for supplying space current to said device over said line from said source, a circuit for supplying heating current for said cathode from a local source, means operable in case of 40 failure of said local source of supply for sending an increased amount of current over said line from said source at said main station, and means at the repeater station for utilizing such increase in current to heat said cathode.
6. A system according to claim 5 in which said local source supplies alternating current to heat said cathode, and said last means includes an inverter for changing the increase in direct current received over said line into alternating current. 5
7. In a telephone system, an east group of lines and a west group of lines extending between stations, space discharge repeaters at the east station for certain of said east lines, a source of current at the west station having a connection from one of its terminals to all of said certain east lines in multiple and having a connection from its other terminal to a plurality of said west lines in multiple, connections at said east station from each of said certain east lines to a respective 10 repeater for supplying space current thereto, the circuit for such space current being completed by way of a connection from such repeater to said west lines in multiple, and a circuit at said east station common to said repeaters and connected between said east lines in multiple and said west lines in multiple for supplying to the cathodes of said repeaters heating current energy received over said lines in multiple from said source at the 15 west station. 20
8. In a telephone system, an east group of lines and a west group of lines extending between stations, space discharge repeaters at the east station for certain of said lines, a source of current at the west station, a circuit supplying current 25 from said source to the space paths of said repeaters comprising said east lines in multiple as one side of the circuit and said west lines in multiple as the opposite side of the circuit, and a current-consuming circuit at the east station 30 common to a plurality of said repeaters and adapted to be supplied with current from said source of current at the west station over said first circuit. 35
